SOLE FOR SHOES

Neal W. Powell, Taneytown, Md., assignor to Cambridge Rubber Company, Cambridge, Mass., a corporation of Maryland

Application February 11, 1958, Serial No. 49,598

Term of patent 7 years

(Cl. D7—5)

I claim:

The ornamental design for a sole for shoes, as shown.
